UNITED STATES PATENT OFFICE

HARRY E. NORVIEL, OF ANDERSON, INDIANA, ASSIGNOR TO DELCO-REMY CORPORATION, OF DAYTON, OHIO, A CORPORATION OF DELAWARE

COINCIDENTAL LOCK

Application filed December 7, 1928. Serial No. 324,364.

This invention relates to coincidental locks for preventing theft or unauthorized use of an automotive vehicle, and particularly to a coincidental lock wherein a key controlled member may be operated to open an ignition switch, and to prevent the use of the gear shift lever or other manual control, to set the motor or vehicle into motion.

The objects of the present invention include the provision of a novel coincidental lock which is durable, reliable in operation, and can be actuated with a minimum of amount of effort. More particularly it is an object of the present invention to provide certain improvements conducive to economy in manufacture of coincidental locks in general.

A further object is to provide a non-demountable and practically indestructible device for the purpose stated, in which a key controlled element may be utilized to open and close an electrical circuit, as the usual ignition circuit, and simultaneously therewith operate a bolting unit, as in the transmission case illustrated here, so as to prevent unauthorized use of the vehicle.

Further objects and advantages of the present invention will be apparent from the following description, reference being had to the accompanying drawings, wherein a preferred embodiment of one form of the present invention is clearly shown.

In the drawings:

Fig. 1 is a view partly in longitudinal section, of coincidental lock embodying the present invention, and is taken partly on the line 1—1 of Fig. 2.

Fig. 2 is an end view of the controller unit for the locking device which is mounted on the instrument board of the vehicle.

Fig. 3 is a sectional view of the controller unit taken on a line 3—3 of Fig. 5.

Fig. 4 is a sectional view of the controller unit taken on the line 4—4 of Fig. 5.

Fig. 5 is a sectional view of the controller unit taken on the line 5—5 of Fig. 2.

Fig. 6 is a sectional view of the controller unit taken on the line 6—6 of Fig. 1.

And Fig. 7 is a sectional view through the

controller unit taken on the line 7—7 of Fig. 1 and showing certain parts in elevation.

In the drawings, 20 designates a metal tube which is formed preferably by bending sheet metal into cylindrical form, and by holding the abutting ends together by any suitable means as by an interlocking joint (not shown). The tube 20 is closed at one end by a lock barrel or plug 21, in a manner to be longitudinally movable therein. Removal of the plug 21 from the case 20 is prevented by means of a screw pin or set screw 22 driven into the plug 21, and having the head thereof confined within the elongated slot 23 of the tube 20. The other end of the tube 20 receives the cylindrical portion 25a of a non-conducting terminal block 25, and is provided with oppositely disposed notches or bifurcations 24 for receiving terminal supporting portions 25b which bear against the portions 26 of the tube 20 which defines the end of the notches 24.

The block 25 insulatingly supports switch contacts 32 which are secured by terminal bushings 33, each receiving a terminal screw 34. As shown in Figs. 1 and 6, each contact plate 32 fits within a recess 38 in the block 25 having parallel sides so that the plate 32 cannot turn while located within the recess 38. The terminal bushing 33 passes through the contact 32, and is provided with a headed member 33a and is held in engagement with the plate 32 as shown in Fig. 1, by riveting over a portion of it as indicated by the numeral 39 against a washer 40 located on the outside of the block 25. This prevents the bushing 33 from turning when the terminal screw 34 is turned.

The contacts 32 are engageable by a resilient ring contact or bridging member 41, insulatingly supported by a non-conducting block or contact carrier 42 which is slidable within the inner end of the tube 20.

The carrier 42 is somewhat cup-shaped in formation, being moulded from insulating material to provide the cup-shaped recess or spring receptacle 43, the hub 44, and the guide lugs 45, which latter are slidably received within the bifurcations 24 of the case 20. Within the body of the carrier 42, are an-

chored the tubular headed inserts 46 which provide a retaining means for the ring contact 41, by the shank portion thereof being received by apertured or notched ears 51 of the ring, and the tubular portions of the protruding inserts being turned over to secure the contact plate 41 against the carrier 42. The spring contact ring 41 is forced out of the planar alignment that it would naturally assume into that form in which the web portions 50 between the attaching ears 51, are angularly disposed with respect to a common plane, as shown in Fig. 1, and when assembled with its carrier 42 within the case 20 in proper relation with the fixed contact carrier 25, will provide for resilient and wiping engagement with the fixed contacts 32, as will hereinafter appear. Centrally of the block 42 and extending longitudinally thereof, is a bore 47, terminating in a countersink 48 centrally of the hub 44.

The countersink 48 provides for the seating engagement of a contact actuating member, which comprises a short tube 52 connected at one end with a cup-shaped member 53 and having one end thereof rolled inwardly as at 54 to provide a seating member to operate with the countersink 44. In the present instance the tube 52 and cup 53 are connected by providing an annular ridge 55 near the opposite end of the tube to provide a seat for the edge of a central opening in the bottom of the cup member, and spinning over the protruding end of the tube 52 against the bottom of the cup as at 56, after the cup has been placed on the tube against the ridge or shoulder. The contact carrier 42 with its associated actuating member are contained within the case 20 with the tube 52 passing through the central aperture 57 of the block 25, and with the cup member 53 disposed between the inner end of the plug 21 and the terminal block 25 so that positive driving engagement will be maintained between the plug 21 and the contact actuator 52. This positive drive is assured by providing the cylindrical wall 60 of the cup 53 at substantially diametric points with apertures 61 for receiving an elongated headed pin 62 provided with a counter bored stem as at 63. The cup member 53 is somewhat smaller in diameter than the bore of the case 20, and consequently smaller than the cross section of the controller plug 21. The inner end of the member 21 is therefore provided with a longitudinal bore or recess 64, into which fits the cup 53. The wall of the bore so formed is provided with the lateral openings 65, which when assembled with the cup 52 within the recess 64 will be in alignment with the apertures 61 in the wall of the cup, and will be of such dimension as to freely receive the enlarged ends of the pin 62 when assembled within the case 20, and prevent any frictional

contact between the pin and the case 20. The contact actuator and the controller plug are assembled as a unit, by inserting the cup 53 within the recess 64 so that the apertures 61 and 65 are in alignment and then inserting the pin 62 therethrough until the counter bored end of the pin can be expanded as shown in Fig. 1. Between the block 25 and the cup member 52 there is placed a compression spring 66 which normally urges the cup and plug members to an extended position, allowing the contacts 32 to be bridged by the resilient member 41.

The inner end of the tube 20, beyond the block 25, is provided with a reinforcing collar 70, permanently fixed thereto as by spot welding, which prevents the removal of the fixed contact carrier 25 from the bifurcated or notched end of the tubular case 20, and provides a housing and protecting inclosure for the switch contacts hereinbefore described. A conduit support 71 is received by the reinforcing member 70, and is permanently fixed thereto as by staking in a number of places, so that a portion of the member 70 is struck into an annular groove 72 about the reduced portions 73 of the support 71 as indicated at 74. Between the inner end of the support 71 and in the receptacle 43 of the contact carrier 42, is disposed a spring 75 normally urging the contact carrier 42, to a circuit closed position, as will be seen by reference to Fig. 1.

The spring 75 is of sufficient strength to move the contact carrier 42 toward the block 25, when so permitted by the retraction of the contact actuator 52 so that the member 41 is brought into engagement with the contacts 32, and flexed somewhat toward the body of the block 42. This flexing of the member 41 while in making and breaking engagement with the contacts 32 presents a wiping action between the contacting surfaces which always insure bright and clean electrical connections.

The plug 21 may, and usually does, embody one of the locking devices well known in the art, which, in this instance, is exemplified by Figs. 3 and 5. Here, the plug 21 is provided with a key cylinder 80 operable in the usual manner to withdraw a spring pressed bolt 81 from an aperture 82 in the adjacent casing or tube 20, upon the insertion and manipulation of the proper key 83 as is usual and well known to those skilled in the art. In the type of plug or lock barrel referred to in this form, it is possible to move the plug 21 from its circuit closed position, in which the end 84 of the bolt 81 is disposed against the inner surface of the tube 20 as at 85, to a circuit open position, which is that position illustrated in Fig. 5, without the use of the key 83, since the bolt 81 rides freely over the portion 85 of the case 20 when the plug 21 is manually depressed or forced in-

wardly to the position as illustrated in Fig. 1. The reverse movement of the plug 21 cannot be accomplished, however, without the use of the proper key 83.

5 Movement of the lock barrel 21 from the circuit closed position to the circuit open position, or the position illustrated in Fig. 1, will move the contact carrier 42 with the cup-member 53 inwardly therewith, against the 10 springs 75 and 66 respectively. The movement of these elements is advantageously applied to the manipulation of a bolting unit, or additional locking unit to prevent the unauthorized manipulation of certain controls or parts of the automotive vehicle connecting the power plant with the driving wheels thereof and is accomplished in this 15 instance by providing a rigid and non-demountable connection between the control unit, and a remotely positioned bolting unit.

20 The endwise movement of the plug 21, with the associated cup 53 and contact carrier 42, is used in this instance to control a member which will prevent operation of the 25 transmission mechanism to connect the engine with the driving axle of the vehicle as appears from the description that follows:

20 The transmission gear shift mechanism is not shown herein, but it will be understood to 30 be enclosed in a case, the presence of which is shown at 90 of Fig. 1, and to include a pair of plates or rods 91 and 92 slidably supported by the case 90 and movable when the gear shift lever is used to connect the engine 35 with the vehicle propeller shaft, in any one of its several selective gears. It will be further understood that when the gear shift lever is in the neutral position, that members 91 and 92 will be located so that notches 40 93 and 94 provided respectively by the members will be located directly adjacent to each other so as to receive a ball 95 which is guided by an opening 96 has communication with a bore 97 extending substantially at right angles to the direction of movement of the 45 members 91 and 92 and provides a retracting recess for the ball 95.

50 The bore 97 is enlarged at the outer end as at 98 and is designed to receive a reduced portion 99 of a sleeve member 100. The sleeve 100 constitutes a conduit support and a guide for a spring pressed locking bolt 101. The locking bolt 101 is slidable within the sleeve 100 and cooperates with the reduced 55 portion of the bore 97, when operated by the control unit described above, to force the ball 95 into the aperture provided by the notches 93 and 94 of the rods 91 and 92 respectively, and consequently prevents longitudinal movement of the members 91 and 92. The bolting unit is retained in non-demountable relation with respect to the gear case 90, by means of the reduced portion 99 thereof being inserted within the enlarged portion 98 of the bore 97, 60 and fixed therein by a pin 102 driven through 65

a portion of the case 90 into an annular groove 103 of the reduced portion 99 of the sleeve.

The control unit and the bolting unit hereinabove described are operatively and non-demountably connected by an armored protective means as follows:

70 The operative control between these units comprises a Bowden wire 110 passing through a sleeve 111 seated within the tube 52 adjacent the cup 53 and is provided with a flange 112 disposed within the cup 53 at the inner end of the plug 21. The end of the Bowden wire 110 is bent into a loop or lateral extension 75 as at 113 to prevent removal or withdrawal of the wire from the sleeve 111 just described. The sleeve and Bowden wire may be secured together in any suitable manner as by soldering, indicated generally at 114.

80 This Bowden wire 110 extends through the tube 52 and the sleeve portions or conduit supports 71 and 100, and is permanently fixed at the other end to the locking bolt 101 in any desired manner. In the present instance the wire 110 is inserted in a longitudinal bore 115 of the bolt 101 and is retained therein by a pin 116 driven through a transverse hole in the bolt 101, to form a loop 117 and force it into a second lateral recess 118 adjacent the longitudinal recess 115. The 85 Bowden wire is encased by a Bowden wire tube 120 which passes through the central apertures of the conduit supports 71 and 100 and which are fixed thereto in the following manner: The sleeve 71 is counterbored as at 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 Secured to the case 20 of the control unit is an angular supporting bracket 130, provided with a hole 131 for supporting the unit, in a convenient position to some part 5 of the vehicle structure.

From the above it will be seen that I have provided a control device simple in construction, effective in operation and which is non-demountable, thus contributing an efficient 10 device to the theft preventative field of the automotive industry.

When assembling the mechanism, the Bowden wire 110 with the attached sleeve 111, is threaded through the tube 52 from the 15 inside of the cup 53 so that the flange 112 is seated against the spun over edge 56 of the tube 52, and disposed within the cup 53, which is then assembled with the plug 21 as has heretofore been described. It will be 20 noted by reference to Figs. 1 and 5 that the pin 62 is disposed in end alignment with and in close proximity to the Bowden wire end assembly as it is positioned within the cup and tube, so that endwise movement of the 25 wire relative to the tube and cup is prevented. This construction insures positive movement of the Bowden wire whenever the controller 21 is moved.

The assembly may then be completed in 30 any preferred order as by threading the wire successively with the spring 66, the tube 20 which is then secured to the plug 21 by means of the screw 22, and followed by threading thereon the block 25, the carrier 42, 35 spring 75, the armored protection means, and finally the bolt 101.

In the operation of my device an inward movement of the lock barrel or plug 21 will move the cup member 53 with its associated 40 contact carrier 42 against the springs 66 and 75 respectively, and open the circuit between the contacts 32 and 41. This movement of the control member will also move the Bowden wire 110 within the tube 120 and reciprocate the bolt 101 within the bore 97 to 45 urge the ball 95 into its locking position as shown in Fig. 1. While the elements are in this position the circuit through the contacts 32 and 41 is open and the manual control elements connected to 91 and 92 are locked in non-operative position. Due to the non-demountable connection of the control unit and bolting unit, and the armored protection afforded through the Bowden wire control, the operative condition of the motor vehicle cannot be reestablished until the proper key 83 has been inserted in the key cylinder 80 to allow a retraction of the plug 21 to its extended or circuit closed position.

When the return of the plug 21 has been 55 made possible, by the insertion of the proper key 83, the springs 75 and 66 acting upon the contact carrier 42 and the cup member 53 respectively, will move the Bowden wire control and plug 21 to the outward position,

which closes the circuit between the contacts 32 and 41 and withdraws the bolt 101 from engagement with the ball 95, thereby making it possible to start the power plant and establish an operative connection between it 70 and the parts associated with the plates 91 and 92.

While the form of embodiment of the present invention as herein disclosed, constitutes a preferred form, it is to be understood that 75 other forms might be adopted, all coming within the scope of the claims which follow.

What is claimed is as follows:

1. In a coincidental lock for automotive vehicles, the combination of a tubular case, a key controlled device movable endwise within the case, a bridging contact movable into and out of engagement with stationary contacts by the key controlled device, spring means disposed against the case urging the 80 contacts to closed position and spring means for returning the key controlled device to initial position.

2. In a coincidental lock for automotive vehicles, a controller member, comprising in 90 combination, a tubular case, a key controlled device movable endwise within and closing one end of the case, a non-conducting block having a part housed by the case and terminal supporting portions without the case, 95 stationary contacts insulatingly supported within the case, a bridging contact movable into and out of engagement with the stationary contacts by the key controlled device, armor supporting means closing the other 100 end of the case, spring means in said case disposed between the said block and control device for returning the control device to normal position, and spring means in said case 105 disposed between said armor supporting means and said bridging contacts.

3. In a coincidental lock for automotive vehicles, a controller member, comprising in combination, a tubular case, a key controlled device movable endwise within and closing one end of the case, a non-conducting stationary contact carrier and terminal block mounted mid-way of the case, a bridging contact carried by the case and movable into and out 110 of engagement with the stationary contact by a contact actuator having engagement with the key controlled device, said contact actuator comprising a tube engaging the bridging contact support and provided with a cup member, positively connected to the said actuator.

4. In a controller for theft preventative devices, the combination comprising, a tubular case, key controlled means movable endwise within the case, a terminal supporting block providing switch contacts, and a movable contact carrier guided by the case, 125 said block being interposed between the carrier and key controlled means, and provid- 130

ing an opening through which said means may actuate the contact carrier.

5. In a controller for theft preventative devices, the combination comprising, a tubular case, key controlled means movable endwise within the case, a terminal supporting block providing switch contacts and a movable contact carrier provided with a spring contact for cooperation with said switch contacts guided by the case, said block being interposed between the carrier and key controlled means, and providing an opening through which said means may actuate the contact carrier.

10 6. In a controller for theft preventative devices, the combination comprising, a tubular case, key controlled means movable endwise within the case, a terminal supporting ring having switch contacts, a contact carrier movable within and guided by the case, said terminal ring being disposed within the case between the contact carrier and said means, and providing terminal members without the case, and provisions connected to said means 20 and positively moving therewith to move said contact carrier away from said terminal block.

25 7. In a controller for theft preventative devices, the combination comprising, a tubular case, key controlled means movable endwise within the case, a terminal supporting ring having switch contacts, a contact carrier movable within and guided by the case, said terminal ring being disposed within the case 30 between the contact carrier and said means, and providing terminal members without the case, actuating provisions connected with said means for moving said carrier in one direction, and additional actuating provisions connected with said means for performing a second function, both of said provisions 35 being positively movable with said means.

In testimony whereof I hereto affix my signature.

45 HARRY E. NORVIEL.
